UNITED STATES PATENT OFFICE.

FRED WEGNER, OF FAIRPORT, NEW YORK, ASSIGNOR, BY MESNE ASSIGNMENTS, TO
UNITED LAST COMPANY, OF AUBURN, MAINE, A CORPORATION OF MAINE.

LAST FOR MAKING FOOTWEAR.

Application filed December 13, 1921. Serial No. 522,130.

To all whom it may concern:

Be it known that I, FRED WEGNER, a citizen of the United States, and resident of Fairport, in the county of Monroe and State of New York, have invented certain new and useful Improvements in Lasts for Making Footwear, of which the following is a specification.

The present invention relates to lasts for making footwear and more particularly to the type in which there is employed a fore or toe part and a rear or heel part, connected together in such a manner that the last may be collapsed and extended at will. An object of this invention is to provide a novel locking means which may be shifted to a position where the last may be collapsed and which upon the expansion of the last, after such collapsing, automatically returns to locking position. A further object of the invention is to provide a novel positive lock in which the locking element may be moved and held out of locking position, so that the accidental return to such position is avoided until the last has been collapsed and again extended. A still further object of the invention is to provide a last with a positive locking means which will hold the last against collapsing and an impositive locking means which will permit the collapsing of the last under pressure, the two locking means being constructed and arranged for substitution, one for the other at will.

To these and other ends, the invention consists of certain parts and combinations of parts, all of which will be hereinafter described, the novel features being pointed out in the appended claims.

In the drawings:

Fig. 1 is a sectional view through a last constructed in accordance with this invention, the last being shown locked in an extended position;

Fig. 2 is a similar view showing the last parts relatively displaced slightly from normal position, the last being impositively locked;

Fig. 3 is a detail view of the bonding means;

Fig. 4 is a section on the line 4—4, Fig. 1;

Fig. 5 is a section on the line 5—5, Fig. 4, showing the locking detent in locking position;

Fig. 6 is a section on the same line show-

ing the locking detent in impositive locking position; and

Fig. 7 is a similar section showing the manner in which the locking detent is held out of positive locking position until the extension of the last.

In the illustrated embodiment of the invention there is provided a toe or fore part 1 and a heel or rear part 2. These two parts are, in this instance, pivotally connected together at 3, a V shaped notch 4 being provided above the pivot to permit the collapsing of the last. The bonding means, in this instance, embodies a pair of plates 5 secured in the kerf in the fore part 1 by pins 6 and spaced apart at 7 to receive a portion 8 of a bonding plate 9 which is in turn secured by pins 10 in a kerf 11 in the heel part 2. A projection 12 extends from the bonding plate 9 forwardly in the V shaped notch 4 and this projection is adapted to move into the kerf in the fore part 1 above the bonding plates 5 when the last is collapsed. The forward end 13 of this projection serves as an abutment for cooperation with the locking member or detent 14.

The locking member or detent 14 is, in this instance, mounted to swing on the fore part 1. This swinging in this embodiment is secured by providing the locking detent 14 with two slots 15 and 16 through which headed pins 17 and 18 extend to secure the locking detent to the front wall of the V shaped notch 4. Suitable means such as a spring 19 secured at 20 to the fore part and bearing against the lower end of the detent 14 serves normally to move the detent 14 toward locking position, whereas downward pressure upon the upper portion 21 of the detent will serve to swing the detent out of locking position and against the action of the spring 19, thus storing energy in the latter to return the detent automatically to locking position after the detent has been released. The detent 14 has a locking surface 14^a on its lateral face which is constructed to just fit under the end of the abutment 13 when the last is in extended position and which thus positively locks the last in extended position. This locking member 14 also has a beveled surface 14^b on its edge, which, if moved under the abutment 13, can be forced aside by sufficient collapsing pressure exerted on the last and thus will per-

mit the last to be collapsed by pressure alone. The detent 14 also has a surface 14^a on its edge between the surfaces 14^a and 14^b which engages the side of the extension or projection 12 on which the abutment 13 is formed when the last is slightly collapsed in order to hold the detent against return movement after being depressed.

The last parts become thus slightly relatively displaced from extended position when the detent is depressed as shown in Fig. 2 to move the positive locking means out of engagement with the abutment, this being due to the tension on the last while the latter is in the shoe. A coöperative relation is thus automatically established between the abutment 13 and the impositive locking surface or means 14^b as the last is further collapsed under pressure, and the detent is forced aside by the pressure between the abutment 13 and the beveled surface 14^b until the abutment slides past the locking member and enters the kerf in the forepart of the last.

When the last is again extended, the locking detent 14 slides back under the end of the abutment 13, thus positively locking the last again.

What I claim as my invention and desire to secure by Letters Patent is:—

1. In a last, a forepart, a heel part, mechanism connecting them and arranged to permit relative movement to collapse the last, an abutment member on one last part arranged to enter the other in collapse, and a locking member on the other last part arranged to engage the abutment positively to hold the last in extended position, said locking member having a surface arranged to cooperate with the abutment when the locking member is moved sideways in the last to permit collapse by pressure.

2. In a last, a forepart, a heel part, mechanism connecting them and arranged to permit relative movement to collapse the last, one of said parts having a kerf, an abutment projecting from the other last part and ar-

ranged to enter the kerf when the last is collapsed, and a locking member normally covering the kerf and engaging the abutment to hold the last positively in extended position, one of the said members above designated as locking member and abutment having a beveled surface arranged to co-operate with the other said member to permit collapse by pressure when the locking member is moved laterally.

3. In a last, a forepart, a heel part, mechanism connecting them and arranged to permit relative movement to collapse the last, one of said parts having a kerf, an abutment projecting from the other last part and arranged to enter the kerf when the last is collapsed, and a locking member normally covering the kerf and arranged to engage the abutment in two relations, to hold the last positively and impositively locked, respectively.

4. In a last, a forepart, a heel part, mechanism connecting them and arranged to permit relative movement to collapse the last, one of said parts having a kerf, an abutment projecting from the other last part and arranged to enter the kerf when the last is collapsed, and a locking member normally covering the kerf and having portions arranged to contact with the abutment in turn to hold the last positively and impositively locked, respectively.

5. In a last, a forepart, a heel part, mechanism connecting them and arranged to permit relative movement to collapse the last, one of said parts having a kerf, an abutment projecting from the other last part and arranged to enter the kerf when the last is collapsed, and a locking member normally covering the kerf and having portions lying beside each other and arranged to contact with the abutment in turn as the locking member is moved laterally over the entrance of the kerf, to hold the last positively and impositively locked, respectively.

FRED WEGNER.
